UNITED STATES PATENT OFFICE.

RUDOLPH BAHR, OF BURLINGTON, WYOMING.

WIRES-GRIP.

1,263,995.

Specification of Letters Patent. Patented Apr. 23, 1918.

Application filed November 17, 1915. Serial No. 62,025.

To all whom it may concern:

Be it known that I, RUDOLPH BAHR, a citizen of the United States, residing at Burlington, in the county of Bighorn and State 5 of Wyoming, have invented certain new and useful Improvements in Wire-Grips; and I do hereby declare the following to be a full, clear, and exact description of the invention, such as will enable others skilled in the art 10 to which it appertains to make and use the same.

This invention relates to a grip structure, which is applicable for use in connection with wire stretchers, clamps of various 15 structures, fire escapes, wire or rope climbing apparatus, and as a grab for removing broken bits or tools from a well.

Another object of this invention is to provide a grip as specified which includes a 20 housing provided with a pair of oppositely disposed inclined slots in which is slidably seated a bolt or gripping member, which gripping member is adapted upon movement in said slot to grip a wire, rope or the like 25 between its surface and the inner surface of one wall of the body or housing out of the grip.

With the foregoing and other objects in view, this invention consists in such novel 30 features of construction, combination and arrangement of parts, as will be hereinafter more fully described, illustrated in the accompanying drawings and claimed.

In describing the invention in detail reference will be had to the accompanying 35 drawings wherein like characters designate like and corresponding parts throughout the several views, and in which:

Figure 1 is a side elevation of a wire 40 stretcher utilizing the improved clamp,

Fig. 2 is a side elevation of the clamp,

Fig. 3 is a top plan view of the clamp,

Fig. 4 is a sectional view on the line 4—4 of Fig. 2,

Fig. 5 is a side elevation of the clamp or 45 grip used as a fire escape,

Fig. 6 is an edge view of the structure shown in Fig. 5,

Fig. 7 is a side elevation of the improved 50 grip constructed for forming a grab for removing broken tools from a well, and

Fig. 8 is an edge view of the grip structure shown in Fig. 7.

Referring more particularly to the drawings, 55 1 designates the body of the clamp which is used in connection with a wire

stretcher or analogous device as indicated in Fig. 1 of the drawings. The body 1 of the grip or clamp is constructed of flat metal, and is U-shaped in cross section, as is clearly 60 shown in Fig. 4 of the drawings, having up-standing legs 2 and 3 and a bight portion 4. The legs 2 and 3 of the body 1 of the grip are provided with slots 5 which align with each other and extend diagonally along the 65 sides 2 and 3, as is clearly shown in Fig. 2 of the drawings, having their outer ends positioned in closer proximity to the bight portion 4 of the body 1 than their inner or upper ends. A bolt or gripping member 6 is 70 slidably positioned within the slots 5 and has heads 7 formed upon each end for preventing the accidental displacement of the bolts. The bight portion 4 of the body 1 has an opening 8 formed therein adjacent to 75 its end remote from the outer end of the body to which opening a link or analogous device indicated at 9 is attached. When the grip illustrated in Figs. 1 and 2, 3 and 4, is used in connection with the wire stretcher, 80 as is shown in Fig. 1 of the drawings, a handle bar 10 is provided which has a plurality of chains 11, 12 and 13 attached thereto. When it is desired to draw the meeting ends of two wires together, one wire is attached to a clamp structure attached to the chain or flexible member 13 and the other wire is attached to a clamp or grip structure attached to one of the flexible members 11 or 12. The ends of the wire are positioned 85 between the bolt or gripping member 6 and the inner surface of the bight portion 4 of the body 1, and when the bolt is moved downwardly within the slots 5, it will securely grip the wire, as is indicated at 94, 90 and between the inner surface of the bight portion 4 and the bolt or gripping member 6, securely holding the wire in place, so that it may be stretched by the operation of the lever 10. By providing the two flexible 100 members 11 and 12, a step by step adjustment of the wire which is attached to the grip or clamp carried by either of the chains 11 and 12, is provided.

The structure of the grip illustrated in 105 Figs. 5 and 6, is particularly adapted for use as a fire escape for wire or rope climbers, and it includes a body 20, which is substantially U-shaped in cross section including sides 21 and 22 and a bight portion 23. 110 The sides 21 and 22 are provided with alining slots 24 formed in the sides 21 and 22,

which sides are positioned at angles to the longitudinal lines of the body 20. A gripping pin 25 is slidably mounted within the slots 24 and it has bars 26 connected to its 5 end and positioned exteriorly of the sides 21 and 22. The bars 26 are pivotally connected as shown at 27, to bars 28 which bars have their free ends connected by a cross rod 29. A handle, rope or any desired 10 analogous device may be attached to the cross rod 29 if it is so desired. A chain or analogous flexible member 30 is attached to the bight portion 23, adjacent to its lower end, and it has a stirrup 31 mounted upon 15 its lower end. In using the structure of grip illustrated in Figs. 5 and 6 for the purpose of climbing a wire, a pair of such devices is ordinarily used, and by actuating the bars 28 and 26, the grip upon a rope or 20 wire, such as is indicated at 33 may be changed as desired. For instance: a person using the device for climbing a wire, would place one of his feet in the stirrup 31 of one of the devices, and operate the bars 28 and 25 26 for securely clamping the wire 33 between the gripping rods 25 and the bight portion of the body 20. After a firm grip upon the wire has been obtained by one of the members 20, the second member would 30 be loosened and raised upwardly upon the wire or rope, after which it would be fastened so as to firmly grip the wire, and one of the feet of the operator placed in the stirrup carried thereby. This operation 35 might be continued until the desired height is reached on the rope or wire. In using this structure as a fire escape, the speed of the descent of a person traveling down the rope or wire could be regulated by adjusting the gripping action by the gripping rod 40 40 through the adjustment of the bars or levers 25 and 26.

The modified form illustrated in Figs. 7 and 8 of the drawings, such as is used for 45 the purpose of grabbing tools such as broken bits or the like from wells, includes a body 40 which may be conical-shaped, cylindrical-shaped or square, as desired, without departing from the spirit of this 50 invention. The body 40 is provided with a pair of angularly disposed slots 41 in which is slidably seated a clamping pin or bolt 42. The bolt or pin 42 has arms 43 and 44 connected to its opposite end, which bars 55 are in turn pivotally connected as is shown

at 45 to bars 46. The bars 46 are pivotally connected at 47 to the body 40 and they have flexible members, such as cord or wire 48 secured thereto and extending upwardly therefrom. 60

A pin 49 extends diametrically through the body 40 upwardly of angularly disposed slots 41 and it has a wire 50 attached thereto, as is shown at 51. When the grab structure is used for the purpose of grabbing 65 pieces of broken bits from the well or the like, the body 40 is lowered into the well, and the cords 48 are slack. When the pieces of bits or tools in the well are engaged by the grip or grab structure, the wires or flexible members 48 are drawn taut which moves the clamping pin 42 upwardly in the body 40 and causes the pin to securely clamp the piece of the bit between the inner wall of the body 40 and the pin 42. After the 70 piece of bit has been securely clamped between the pin 42 and the wall of the member 40, the entire structure is withdrawn from the well through the medium of the wire 50. 75

In reducing the invention to practice, certain minor features of construction, combination and arrangement of parts may necessitate alteration to which the patentee is entitled provided such alterations are 80 comprehended within the scope of what is claimed.

What is claimed is:—

A grip structure as specified comprising 85 a frame of U-shaped form in cross section and embodying a base and side pieces, said 90 side pieces being provided with a pair of aligned angularly disposed slots, a clamping pin extending through and slidably mounted within said slots, operating bars pivotally 95 secured to the outer surfaces of the side pieces, links pivotally connecting the operating bars and the ends of the clamping pin, and enlarged heads formed on the ends of said clamping pin and engaging said 100 links to prevent accidental removal of the same by lateral movement of the clamping pin.

In testimony whereof I affix my signature in presence of two witnesses.

RUDOLPH BAHR.
